UNITED STATES PATENT OFFICE.

JOSEPH M. SHERIFF, OF MERCER, PENNSYLVANIA.

FENCE.

SPECIFICATION forming part of Letters Patent No. 396,299, dated January 15, 1889.

Application filed October 19, 1888. Serial No. 288,555. (No model.)

To all whom it may concern:

Be it known that I, JOSEPH M. SHERIFF, a citizen of the United States, residing at Mercer, in the county of Mercer and State of Pennsylvania, have invented certain new and useful Improvements in Fences, of which the following is a specification, reference being had therein to the accompanying drawings, in which—

10 Figure 1 represents a side elevation of a fence-panel constructed according to my invention; Fig. 2, a perspective view of one picket and the contiguous portions of the horizontal fence-wire rails; Fig. 3, a detail 50 sectional view, slightly enlarged to show more clearly my new method of securing the pickets to the fence-rails; Fig. 4, a similar view showing the fastening-wire continuous.

15 The invention has for its objects to provide an extremely simple, inexpensive, and practical method of securing pickets to the horizontal rails of a fence by means of peculiarly-constructed wire fasteners, as will more fully hereinafter appear.

20 In the drawings annexed, A A designate two ordinary fence-posts, between which are tautly stretched suitable horizontal wire rails, B B. Wire rails are shown, and are preferred in carrying out my invention; but it is evident that other rails may be employed, if found 55 desirable or advantageous.

25 The pickets C are secured to the horizontal wires B, at their intersection with the same, by means of wire fasteners D, the pickets being preferably held up off of the ground, as shown. These fasteners each consist, preferably, of a single piece of wire bent into proper shape by means of suitable tools.

30 Each fastener is constructed as follows: One 40 end of the wire is securely attached to the fence-rail B by twisting it around the same, as shown at a, the free end of the wire being carried around in front of the picket and passed through a horizontal aperture, b, in the 45 same. The wire is then bent around the fence-

rail and passed back again through hole b, forming a loop, c, through which the fence-wire B passes. The end of the wire is then carried to the other side of the picket and secured to the main wire again, as at a. Instead 50 of first securing the end of the wire to the rail, as above described, it is evident that any other method of applying the fastener may be adopted. For instance, the wire may be bent about midway its length to form the loop c and the 55 two ends of the wire then passed through the hole in the picket and bent around and secured to the fence-rail upon opposite sides of the picket.

It is evident that instead of using separate 60 wires for each picket, as shown in Figs. 1, 2, and 3, (which construction I prefer,) several or any number of them may be formed of one piece of wire, as shown in Fig. 4.

The fastener as thus constructed is easily 65 applied and will effectually prevent the pickets sagging. It also avoids the use of grooves or staples in the same to bind the pickets to the rails. An important advantage of this 70 particular construction of fastener lies in the fact that the greater the tendency of the pickets to sag the greater will be the force exerted by the fasteners to bind them to the rails.

Having thus fully described my invention, what I claim as new, and desire to secure by 75 Letters Patent, is—

The combination, with a fence rail and picket, the latter being bored or punctured horizontally, as at b, of a wire fastener, D, secured to the fence-rail at its ends and provided with a loop, c, said loop passing through the hole in the picket and embracing the fence-rail, substantially as described.

In testimony whereof I affix my signature in presence of two witnesses.

JOSEPH M. SHERIFF.
